UNITED STATES PATENT OFFICE.

FRANK S. LOW, OF NEW YORK, N. Y.

PROCESS OF MAKING GASOLENE.

1,192,653.

Specification of Letters Patent. Patented July 25, 1916.

Application filed April 24, 1913. Serial No. 763,387.

To all whom it may concern:

Be it known that I, FRANK S. Low, a citizen of the United States, residing at New York, in the county of New York and State 5 of New York, have invented certain new and useful Improvements in Processes of Making Gasolene, of which the following is a specification.

This invention relates to processes of making gasolene; and it comprises a method of 10 making low-boiling hydrocarbons from high-boiling hydrocarbons which comprises subjecting such high-boiling hydrocarbons while in a finely divided or atomized liquid 15 state to suitable conditions of heat and pressure within a specially designed chamber as by spraying against a heated surface in a chamber of less temperature wherein a suitable pressure prevails and then withdrawing, cooling or condensing the products of 20 the process for subsequent distillation or purification; all as more fully hereinafter set forth and as claimed.

Crude petroleum on distillation yields a 25 number of fractions of different boiling points, the amount of each fraction of course corresponding more or less closely with the amount originally contained in the oil. But the demand for the lower-boiling fractions, 30 or the naphtha and gasolene fractions, is at present out of all proportion to the demand for the higher boiling fractions, the kerosene, spindle oils, fuel oil, etc.; this of course being largely due to the great use of internal combustion engines. By "cracking" 35 the oil during distillation the yield of low-boiling fractions may be somewhat increased; but the action is not as fargoing as can be desired.

The object of the present invention is to 40 provide a simple, cheap and ready method of increasing the yield of low-boiling fractions at the expense of the high boiling. To this end I may spray or atomize or otherwise 45 momentarily contact liquid high-boiling oil against or with a heated surface at a temperature above the boiling point of the particular oil, and preferably at a temperature rather far above, the action being under 50 any desired pressure, above or below atmospheric, but generally above. This heated surface I maintain within a chamber of less temperature, so that the oil and the products of its decomposition on leaving such surface

are cooled at once below the decomposing 55 temperature. For instance, in treating a fuel oil or residuum I may project it against a surface maintained at a temperature of say 500° to 1200° F., this surface being so placed as to permit liquid oil to drip or fall off it 60 at once. If I am endeavoring to make oily products of a boiling point less than 212° F., in one form of my invention the chamber may advantageously be maintained at about 212° F. and a circulation of a gaseous 65 carrier may be maintained from the chamber to and through appropriately cooled condensing means. In so operating, any gasolene formed is at once removed from the sphere of reaction and high heat and can 70 undergo no further change. If the chamber and the liquid oil within it are at a temperature above 212° F., naturally such oil does not retain much or any of the low-boiling fraction. The oil dripping off the 75 treating surface may of course be returned for re-projection or it may be removed and the low boiling bodies which have been formed and have dissolved in it may be distilled off. 80

Any suitable high-boiling petroleum oil may be used for my purpose but I advantageously use the grades known as fuel oils; i. e., high boiling residua from petroleum; residua which have been freed by ordinary 85 distillation of their gasoline and kerosene components. However, crude oil itself may be used. High-boiling crudes are particularly suitable.

The petroleum oils consist for the most 90 part of hydrocarbons in which many carbons are united in a chain-like arrangement. In the high boiling oils the chains may run from 15 to 25 carbon atoms. The low boiling bodies which I desire to get in 95 the present invention will run from 5 to 8 carbon atoms. The first influence of heat upon hydrocarbons of this nature is to break apart the union between the carbons; to form shorter chains by breaking apart the 100 longer. If time enough be given the long chains will break down into 1, 2 and 3 carbon groups which are gaseous bodies; and the effort in the present invention is to restrict the breaking down to form bodies of 105 somewhat higher complexity. This I have discovered I can attain by the described method of short-time contact. If the con-

tact of the hydrocarbons with the heated surface be long continued, gaseous bodies are formed; and these gases in turn may break down further to form tarry bodies, coke, etc. This I desire to avoid.

- 5 The character of the heated surface is not a matter of indifference as each particular material exercises a specific effect. But for the most purposes I desire to avoid any 10 special catalytic effect, except as hereafter noted, and therefore employ smooth plates or the like giving a relatively small surface exposure. Rough surfaces prolong the period of liquid contact somewhat. Where a 15 catalytic effect is desired, the heated body is preferably rough or porous to increase the surface. Terracotta, pumicestone, iron, steel, nickel, copper, etc., may all be used and each exercises a specific effect. Iron and 20 steel surfaces usually exercise a comparatively simple analytic or breaking down effect upon the oil molecules. Nickel, especially if freshly reduced, exercises for most purposes too much of a similar effect. Copper 25 coated with fine copper freshly reduced from the oxid is a catalyst intermediate between nickel and iron. The source of heating for the heating surface may be as desired. Electric heating is often convenient.
- 30 Fire heating may also be employed.

In breaking down the complex high-molecule hydrocarbons, some fractions of the products obtained are unsaturated; and for some purposes the unsaturated gasolenes are 35 not desired. In breaking down hydrocarbons by cracking since the broken down products need a greater ratio of hydrogen to carbon to be saturated than do the original hydrocarbons and since the cracking is 40 attended with the production of more or less gas with a high ratio of hydrogen to carbon, cracking is always attended with the production of unsaturated bodies. Under 45 the familiar laws attending dissociative actions, such as cracking, the tendency of gas to form is, in a measure, inversely as the prevailing pressure and by maintaining as high a pressure as possible in the cracking chamber of the present device the percentage 50 of saturated bodies in the resultant gasoline will be materially increased; this increase being due to the decrease in the amount of hydrogen-rich gas which can be formed. As in the present invention the 55 high temperature necessary for cracking is confined to a surface of relatively small area in a chamber of relatively low temperature pressures within such chamber can easily be maintained at a much higher point 60 than is possible where the whole chamber is maintained at cracking temperature.

By a further development of my process, if desired, these unsaturated compounds may be converted into saturated. To do 65 this, I employ an atmosphere of hydrogen

or blue water gas in the treating vessel and use an active catalyst, such as nickel, cobalt, or copper, on the face of the heated surface. The well known catalytic hydrogenating property of nickel which is shared to a less degree by iron and by copper, causes the union of hydrogen with the unsaturated hydrocarbons as they are produced and the formation of saturated hydrocarbons therefrom. A hot nickel surface in an atmosphere 75 of hydrogen or blue gas is particularly advantageous in causing the formation of saturated gasoline from heavy oils projected against such surface.

In the accompanying illustration I have 80 shown, more or less diagrammatically three embodiments of the many types of apparatus which may be used in the described process.

In this showing Figure 1 is a vertical section of an electrically heated type; Fig. 2 is a similar section of a fire heated device; and Fig. 3 is a similar view of a modification with electrically heated contact mass and operating in a somewhat different way. 85

In the showing of Fig. 1, element 1 is a casing of any suitable material, such as steel, adapted to withstand as much pressure as may be desired. As shown, it is provided with jacket 2 and interior coils 3 90 which may be used for heating or cooling as the case may be. Either or both may be used. At its upper portion, it carries an electric heater 5 shown as a concave element carried on stem 6 of insulating material and supplied with current by 8 and 9. This heater may be maintained at any desired temperature and is always hotter than the surrounding chamber. Communicating with the chamber is a valved pipe 10 which 100 may be used for adjusting the pressure in the retort or may be used to supply any suitable gas thereinto. Valved blow-off 11 allows venting the chamber when desired. Set immediately below this heating element 110 is spray nozzle 12 supplied with oil under suitable pressure from pipe 13 and pump 14. At its lower portion, the casing tapers to outlet 15 carrying a weighted valve 16 and leading into collecting reservoir 17, provided with draw-off 18 and gas escape tube 19. This reservoir may be provided with cooling jacket 17a. Tube 19 may be, as shown, provided with a reflux condenser arrangement 115 20. 120

Another form of apparatus is shown in Fig. 2. In this figure, 21 is a casing of any suitable size, shape or material having inset in one wall heating element 22, which may be of copper or other readily conductive metal. As shown it is set in a vertical position. Heat is supplied to it by gas burner 23 which maintains it at a much higher temperature than the rest of the chamber. Oil is fed to the chamber through valved inlet 125 130

24 and may be removed from the chamber through valved outlet 25. Coils 26 in the chamber provide for control of temperature and may be supplied with heating or cooling media. Within the chamber is set an injector nozzle 27 drawing oil from the chamber itself through 28 and supplied with projecting fluid under pressure from pipe 29. This pipe may be supplied with steam from 30 or with gas under pressure from 31. At its upper end the chamber is provided with vapor and gas outlet 32 having a pressure valve 33 which may be set to any desired loading. This outlet 10 is prolonged through condenser 34 and ends in collecting receiver 35. This receiver is provided with vent 36 and draw-off 37. From it leads gas return pipe 38 to pump or fan 39. This fan or pump may supply gas 20 to conduit 31 to operate the injector. Beyond the pump is a branch conduit 40 leading to the gas burner 23.

The device of Fig. 3 is substantially like that of Fig. 1, save that the vapors are removed from the residual oil as fast as formed. In this showing, 41 is a casing, 42 are temperature controlling coils, 43 is a valved inlet for oil, 44 an outlet for oil, 45 is an electrical heating surface against 30 which oil picked up from the interior of the tank through 46 is projected by spray nozzle 47 supplied with gas by pipe 48 and pump 49. Vapors and gas pass outward through 50 and condenser 51, and condensed 35 gasoline is collected in tank 52, whence it may be removed through outlet 53. Gas may be vented out through 54 or sent back through 55. 56 allows the introduction of gas from other sources, such as hydrogen, 40 blue water gas, etc.

In the operation of the structure of Fig. 1, oil is continuously supplied through 14 and 13 to the projecting nozzle and is then sent against heating element 5. This causes 45 the formation of a greater or less proportion of gasoline or kerosene which is dissolved by the unchanged heavy oil and falls to the bottom for escape through 15 into the tank 17. When a body of oil is kept in the tank 50 cooling fluid may be used in the jacket or coils. The mixed oils from 17 may be removed to any suitable still (not shown) and distilled to regain gasoline and kerosene. Residual heavy oil may be sent back. Condenser 20 returns any gasoline that may pass 55 away with the gas through 19. If desired, hydrogen may be introduced through 10, and 5 may be covered with a catalytic metal.

In the operation of Fig. 2, production and removal of gasoline, or of gasoline and kerosene, are continuous, the chamber being kept at a temperature suitable to maintain these bodies in a vaporous condition.

Oil is introduced from time to time through

24 to form a body of oil, and oil is picked up at 28 and sent against heated surface 22. The oil drips back for re-passage. The gasoline vapors formed are carried forward by the gas entering through 29 and, passing onward through 32, past 33 are condensed out by 34 and accumulate in 35. Some gas is always formed in the action and the excess of such gas as is formed may be vented through 36 but the temperature of 22 while of course maintained high enough to break down high boiling oils into low boiling oils, is not maintained high enough to cause the formation of any substantial amount of gas. A portion of gas is 80 sent through 40 to maintain heat. Another portion of the gas may be sent through 31 to act as projecting means. Alternatively steam or hydrogen may be sent through 30.

The operation of Fig. 3 is much the same 85 as Fig. 2, the difference being mainly in the substitution of electrically heated surface 45.

The apparatus may be worked under any pressure desired. Some pressure above that 90 of the atmosphere is usually desirable; but of course pressures below atmosphere may also be used for specific purposes.

What I claim is:

1. The process of converting high boiling 95 oils into lower boiling oils which comprises contacting such a high boiling oil in the form of a spray against a localized heated element maintained at a sufficient temperature sufficient to crack said high 100 boiling oils into low boiling oils while insufficient to form substantial amounts of gas, said element being in a chamber of less temperature, collecting the vapors and gases 105 and condensing the vapors of low boiling products formed.

2. The process of converting high boiling 110 oils into lower boiling oils which comprises contacting such high boiling oil in the form of a spray against a localized heated element contained in a chamber under greater pressure than atmospheric and of less temperature than said element, said heated element being maintained at a temperature sufficient to crack said high boiling 115 oils into low boiling oils while insufficient to form substantial amounts of gas, collecting the vapors and gases and condensing the vapors of low boiling products formed.

3. The process of converting high boiling 120 oils into lower boiling oils which comprises maintaining a body of such oil in a still at a temperature below that at which any substantial distillation or cracking of such oil 125 will take place, maintaining a heated element within such still at a temperature above the cracking temperature of such oil and continuously spraying oil from such body against said element while allowing unchanged high boiling oil to flow back to such 130

body and removing vapors of cracked products.

4. The process of converting high boiling oils into lower boiling oils which comprises maintaining a body of such oil in a still at a temperature below that at which any substantial distillation or cracking of such oil will take place, maintaining a heated element having a surface of catalytic material within said still at a temperature above the cracking temperature of such oil and continuously spraying oil from such body against said element while allowing unchanged high boiling oil to flow back to such body and removing vapors of cracked products.

5. The process of making gasoline and kerosene which comprises atomizing liquid high-boiling petroleum material by a gas comprising hydrogen under pressure against a surface heated to a temperature above the boiling point of such material and contained in a chamber of lower temperature than such surface and recovering low boiling oils thereby produced.

6. The process of making gasoline and kerosene which comprises atomizing liquid high-boiling petroleum material by a gas comprising hydrogen under pressure and projecting the atomized material against a catalytically acting surface heated to a temperature above the boiling point of such material and contained in a chamber of lower temperature than such surface and recovering low boiling oils thereby produced.

7. The process of converting high boiling oils into lower boiling oils which comprises maintaining a body of such oil in a still under pressure but at a temperature below that at which any substantial distillation or cracking of such oil will take place, maintaining a heated element within such still at a temperature above the cracking temperature of such oil and continuously spraying oil from such body against said element while allowing unchanged high boiling oil to flow back to such body and removing vapors of cracked products.

8. The process of converting high boiling petroleum oils into lower boiling oils which comprises establishing and maintaining a body of oil in a suitable chamber under a pressure higher than atmospheric and at a temperature below the cracking point while maintaining the temperature of a heated element above such oil body and within such chamber at a materially higher temperature, a temperature sufficient to cause cracking decompositoin of oil, and continuously spraying oil from said body against said surface and allowing unchanged liquid to

flow back to said body while removing and collecting produced cracked products.

9. The process of converting high boiling petroleum oils into lower boiling oils which comprises establishing and maintaining a body of oil in a suitable chamber at a temperature below the cracking point while maintaining the temperature of a heated element above such oil body and within such chamber at a materially higher temperature, a temperature sufficient to cause cracking decompositoin of the oil, and continuously spraying oil from said body against said surface and allowing unchanged liquid oil to flow back to said body while removing and collecting produced cracked products.

10. In the conversion of high boiling petroleum oils into lower boiling oils the process which comprises maintaining a body of such high boiling oil in a still chamber at a temperature below its own boiling point while continuously spraying abstracted portions of said body of oil against a localized heated area located in said still chamber above said oil body and having a surface of catalytic material, said heated area being maintained at a temperature above the cracking point of said high boiling oil and recovering the low boiling cracked products formed.

11. The process of making gasoline and kerosene which comprises atomizing liquid high-boiling petroleum material by a gas comprising hydrogen under pressure against a surface heated to a temperature above the boiling point of such material, such surface being in a chamber under pressure above that of the atmosphere and such chamber being of lower temperature than such surface and recovering low boiling oils thereby produced.

12. The process of making gasoline and kerosene which comprises atomizing liquid high-boiling petroleum material by a gas comprising hydrogen under pressure and projecting the atomized material against a catalytically acting surface heated to a temperature above the boiling point of such material, such surface being in a chamber under pressure above that of the atmosphere and such chamber being of lower temperature than such surface and recovering low boiling oils thereby produced.

In testimony whereof, I affix my signature in the presence of two subscribing witnesses.

FRANK S. LOW.
